UNITED STATES PATENT OFFICE

112,890

DESIGN FOR A DUAL FLUSHING VALVE

Roy H. Zinkil, Oak Park, and Edward A. Fredrickson, Chicago, Ill., assignors to Crane Co., Chicago, Ill., a corporation of Illinois

Application June 18, 1938, Serial No. 77,921

Term of patent 14 years

To all whom it may concern:

Be it known that we, Roy H. Zinkil and Edward A. Fredrickson, citizens of the United States, residing in the county of Cook and State of Illinois, whose post office addresses are 406 N. Cuyler Ave., Oak Park, Illinois, and 5956 Manton Ave., Chicago, Illinois, respectively, have invented a new, original, and ornamental Design for a Dual Flushing Valve, of which the following is a specification, reference being had to the accompanying drawings, forming part thereof.

Fig. 1 is a front view of a dual flushing valve showing our new design.

Fig. 2 is a plan view of the valve.

Fig. 3 is a rear view of the valve, the dotted lines indicating passages therefrom.

Fig. 4 is a bottom view of the valve.

Fig. 5 is an end view of the valve.

Fig. 6 is an opposite end view of the valve.

The dominant features of the design reside in the portions shown in full lines.

We claim:

The ornamental design for a dual flushing valve, substantially as shown and described.

ROY H. ZINKIL.

EDWARD A. FREDRICKSON.
